CHARLES DE MINICO, OF REVERE, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,009,054.

Specification of Letters Patent. Patented Nov. 21, 1911.

Application filed December 12, 1906, Serial No. 347,526. Renewed November 30, 1910. Serial No. 594,974.

To all whom it may concern:

Be it known that I, CHARLES DE MINICO, a citizen of the United States, residing at Revere, in the county of Suffolk and Commonwealth of Massachusetts, have invented certain Improvements in Lasting-Machines, of which the following description, in connection with the accompanying drawings, is a specification, like reference characters on the drawings indicating like parts in the several figures.

This invention relates to lasting machines. The machine in which the invention is herein shown as embodied has been designed particularly for lasting the fore parts of "turn" shoes. A turn shoe is a shoe which is assembled and lasted with the flesh side of the sole outermost and those portions of the upper material on the outside which are to be on the inside of the shoe when it is finished. The shoe is assembled in this way to facilitate the operation of sewing the upper directly to that side of the sole which is to be on the inside of the finished shoe. After the lasting and sewing operations the shoe is turned right side out. In making turn shoes it is a present practice for the operator who prepares the shoe for the machine to place on the bottom of an inverted last a sole which has usually been prepared by cutting away the marginal portion of the flesh side around the fore part and the shank sides to form a thin edge and a shoulder. A slit is also usually cut into the same side of the sole and inclined downwardly and outwardly toward the shoulder to form a channel for receiving the seam which is to connect the upper to the sole and a lip for covering the seam. The sole is arranged with its flesh side up and is tacked to the last at several points. The upper materials, assembled with the linings outside and the finished side of the leather inside, are then adjusted upon the last and the edges drawn over the innersole and secured by tacks at the forward ends of the heel stiffener and, if desired, at a sufficient number of points along the shank and ball to last the sides of the shoe. The shoe is then ready for presentation to the machine of the present invention by which the toe is lasted.

In lasting a turn shoe it is very important to draw the lining tightly, and it is

preferable that it be drawn relatively 55 tighter than the upper because it is essential to good lasting that the lining be free from wrinkles when the shoe is turned right side out. Inasmuch as the lining must be stretched while it extends over or outside 60 of the upper and is to be reversely turned so that it extends inside of the upper on a relatively shorter line about the last, the lining should for the best result be stretched more than the upper. In hand lasting the 65 operator frequently pulls the upper and the lining separately, whereby he is able to give a light pull to the upper and then a stronger pull to the lining to stretch it thoroughly. It is also frequently desirable in lasting 70 turn shoes, and other types of shoes as well, to pull the upper materials at one portion of the shoe more than at other portions, and sometimes to pull one shoe more than another. An important feature of this invention consists in providing means by which an operator can regulate the movements of the machine to cause it to impart at different times, for the purpose of drawing the marginal portion of the upper inwardly 80 from the edge of the sole, pulling movements of different lengths in accordance with the requirements of the particular portion of stock engaged by the pulling means. This regulation may be required to enable 85 the machine to give the required relative pulling strains to different layers of the upper material, or to give pulling movements of different lengths to different parts 90 of the same shoe or to different shoes, as, for example, to give a shorter pulling movement from gripping position inwardly over the last bottom while a short upper is being pulled than when an upper of normal length is being operated upon so that overstraining or tearing of the stock may be 95 avoided.

In machines as heretofore constructed means has been provided for readily adjusting the tension of a spring through 100 which the movements of the grippers are effected for updrawing the upper. In practice it may be found desirable to adjust the tension of the updraw spring for reducing the updrawing strain at the same time that the length of the overdrawing movement of the grippers is reduced and vice versa. Means is therefore provided, in accordance 105

with one modification herein shown, whereby the device for controlling the tension of the updraw spring and the device for regulating the overdrawing stroke of the grippers may be actuated simultaneously. In addition to their movements for updrawing and overdrawing the upper the grippers have movements laterally for plaiting the upper at times. This lateral movement is effected yieldingly through a spring and it is desirable to be able to regulate the tension of this spring readily while the machine is running. For this purpose I have provided a tension-regulating means by which the operator may either increase or decrease the tension of the plaiter spring by a single movement of the hand, and the tension-regulating means is automatically locked in the position to which it is adjusted. I have also made an improvement in the bottom rest against which the shoe is held while being operated upon.

The several features of the invention, including certain details of construction and combinations of parts, will be explained in the following description and pointed out in the claims.

In the drawings, which represent a preferred embodiment of my invention in a machine of the type known as the "hand method" lasting machine, an example of which is shown in Letters Patent of the United States, No. 584,744, granted June 15, 1897, Figure 1 is a side elevation; Fig. 2 is a perspective view of a turn shoe the toe of which has been lasted upon the machine shown in Fig. 1; Fig. 3 is a front elevation of the machine; Fig. 4 is a perspective view of the plaiter-spring adjusting means; Fig. 5 is an elevation of the machine from the side opposite to that shown in Fig. 1; Fig. 6 is a rear elevation of a portion of the machine for the purpose of illustrating mechanism for regulating the overdrawing movement of the grippers; Fig. 7 is a perspective view on a larger scale, showing some of the principal instrumentalities concerned in the lasting operation and a shoe in operative relation thereto. Fig. 8 shows, in section, a shoe, the upper of which is being pulled by the lasting grippers while the downhold is retaining the feather-edge of the sole against displacement by the upper being strained, and the presser occupies its retracted position; Fig. 9 is a similar view of the shoe on a plane nearer to the observer and shows the relative positions of the several parts when the grippers have released the stock and the wiper is holding the upper in the angle of union between the feather-edge and shoulder of the sole and pressing the wire into binding engagement with the upper; Fig. 10 is a side elevation showing a modification; and Fig. 11 is a detail rear elevation of parts shown in Fig. 10. Fig. 12 is a side

elevation of the starting and stopping mechanism, including the controlling treadle and a portion of the connection between said treadle and the cutting mechanism.

The standard 2 of the machine supports a frame or head 4, in which the driving shaft 6 is mounted to turn and with relation to which other parts are supported for movement as will be described. The shoe is presented to the machine with the bottom uppermost against a bottom rest 10 and is pressed laterally against an edge rest 8 in position to be operated upon by the grippers, the presser, and other mechanisms of the machine.

The grippers, which comprise jaws 14 and 16, are carried by bars 13 and 15, the bar 13 being formed as a tube and receiving the bar 15 within it as may be seen in Fig. 7. The bar 13 is connected at its upper end by a ball and socket joint with the front end of a lever 18, which is pivoted at 20 to the frame and is connected at its rear end with a cam 280 on the driver-shaft 6. This connection between the lever 18 and the cam 280 comprises a block 21 pivoted to the rear end of the lever, a block 22 normally resting on the block 21, and a spring 23 secured at adjusted tension by a nut 24 on a rod 25. The rod extends downwardly through openings therefor in the blocks 21 and 22 and the lever 18 to a cam roll which stands in a cam groove in the front face of the cam block 280. Between the blocks 21 and 22 is arranged a wedge block 26 having one or more seats, as 27 and 28, shown in Fig. 10, and an operating rod 29 which extends through guides in the lever 18 to the front of the machine where it is provided with a handle 30. The grippers are yieldingly uplifted by means of the lever 18, actuated through the spring 23, the tension of which is initially adjusted by the nut 24. The tension of this spring and consequently the force with which the grippers are uplifted may be varied by moving the wedge at any time during the operation of the machine, as, for example, when it is desired to strain more or less than usual any particular shoe or a particular portion of the upper stock engaged by the grippers. The grippers are moved downwardly by the lever 18 into position to grip the stock and are then closed by forcing the gripper bar 15 downwardly in the bar 13. This movement is effected by a rock-shaft having the arms 32, 34, and journaled in bearings formed on the lever 18, as shown most clearly in Figs. 1 and 3. The arm 32 carries a yielding plunger resting on the upper end of the bar 15. The arm 34 carries a roll which is engaged by an edge cam 35, which turns the rockshaft in the direction to close the grippers. The grippers are opened, when the cam permits, by a reverse movement of the bar 15 effected by a spring 130

36 acting on a pin 37 which extends from the bar 15 through a slot in the bar 13, as shown in Fig. 1.

The grippers are given movements outwardly from the machine for drawing the upper over the sole on the bottom of the last, and to this end the bar 13 is extended through a block guide 40 which is supported by the forked front end of a longitudinally 10 movable slide rod 42, which is mounted in the frame and carries a roll 44 for engagement with a cam 46 by which the slide rod is moved rearwardly to draw the grippers toward the machine and into their gripping 15 position. Reverse movement of the slide rod 42 for actuating the grippers to pull the upper over the last is effected by a spring-actuated arm 48, the spring for which may have its tension varied by means of the arm 20 25 49 which is secured in adjusted position by a pawl and ratchet, as shown in Fig. 5. As has been explained, it is important to regulate the pull effected by the grippers in accordance with the different requirements of different shoes and different portions of the 30 upper material of the same shoe, and for this purpose means is provided which is under control of the operator and which can be adjusted while the machine is running 35 for controlling the movement of the grippers to pull the upper materials over the last. The mechanism by which this is accomplished may be varied, but in the machine herein shown a readily operable device is 40 arranged for limiting the range of movement of the grippers by adjustably limiting the movement of the slide rod 42. To this end a rockshaft 50 is arranged in bearings in the frame, as shown in Figs. 1, 3, 6 45 and 10, and has an arm 52 connected to a slide 54 which is forked at its free end to embrace the slide rod 42. The slide 54 is arranged to be guided between a rear face 55 of the frame and a bracket 56 and to extend more or less between said face 55 of the 50 frame and the head 45 of the slide rod where it forms a stop to limit positively the normal length of movement or stroke of the grippers inwardly over the edge of the last 55 in overdrawing the upper. The forked ends of the sliding stop 54 may be of uniform thickness, as in Fig. 6, or may be relatively thin at their end portions, as shown in Figs. 10 and 11, so that when said end portions are interposed a limited distance between the head 45 and the face 55 they will shorten the range of movement of the grippers to a certain extent. When the slide is further introduced between the head and frame 60 the thicker portions x' will shorten to a greater extent the stroke of the grippers for pulling the upper over the last. It will be observed that in thus regulating the movement of the grippers for pulling the upper 65 materials over the bottom of the shoe the

gripping position remains the same and the outer limit of the movement is varied.

For actuating the rockshaft 50 there is shown in Figs. 1, 3 and 6 an arm or handle 58 applied in convenient position to be reached by the operator. A spring 59 connected to the arm and to the fixed part holds the arm and parts controlled by it in the positions to which they are adjusted.

In Figs. 10 and 11 is shown a modification in which the slide 54 is arranged to be actuated simultaneously with the adjustment of the wedge block 26. An arm 60 replaces the handle 58 and is connected by a link 61 with one arm of an elbow lever 62 fulcrumed on the lever 18 and having its other end joined to the wedge block by a link 64 so as to be actuated by the slide rod 29. The connection between the arm 60 and the rockshaft 50 is made yielding through the spring 65 so that movement of the operating handle may take place at any time, and if the head 45 of rod 42 prevents the immediate adjustment of the stop slide 54 when the slide rod 29 is moved the spring 90 will effect such adjustment when the rod 42 is retracted. With this construction, the force of the spring 23 through which the uplifting movement of the grippers is effected and the extent of the forward movement of the grippers may be varied by the same adjustment. It sometimes occurs that in the rapid reciprocation of the slide rod 42 forwardly and backwardly the grippers are drawn backwardly by their momentum beyond their gripping position adjacent to the edge of the last and therefore do not properly grip the stock and sometimes strike against other parts of the machine. To prevent this overthrowing of the grippers the 105 slide rod 42 is shown as provided with an adjustable stop 43 arranged in position to engage the frame of the machine if the rod is carried backwardly too far by the momentum of the moving parts.

Mechanism is provided, which is arranged to be rendered operative at the will of the operator, for giving to the grippers movements for plaiting the upper. This mechanism includes means for moving the grippers laterally from one side of the median line of the machine, in which they usually operate, to positions at either side of the median line. To this end a knee lever 68 is provided, the rear arm of which has an inclined guideway, as shown in Fig. 5, receiving a roll 71 on a vertical rod 70 which, through a bell-crank lever 72, controls the position of a sliding collar 74 on a sleeve shaft 75. The sleeve shaft receives a rockshaft 76, which has a stud 78 extending through a spiral slot 79 in the sleeve shaft and into the sliding collar 74. Movement of the collar 74, forwardly or backwardly, by the knee lever 68 therefore adjusts the 110 115 120 125 130

rockshaft 76 which carries on its front end a pinion 80 that meshes with a rack on a segmental block 82. The segmental block is guided in a rocking head 35 carried by the sleeve shaft 75. The sleeve shaft and its head 85 are continuously oscillated by a lever 86, pivoted to the frame and having on one end, see Figs. 3 and 5, a sector and on its other end a roll standing in a groove 10 in the side of the cam block 33 by which the grippers are closed as before described. Movement of the knee lever acts through the parts described to set the segmental block 82 in the center, or at either side of the center, of oscillation of the head 85. The grippers are connected with the segmental block 82 for movement laterally and also rotatively for plaiting the upper when this disposition of the upper material is required 20 to take care of the fullness of the marginal portion of the upper materials about the toe of the shoe. The segmental block 82 may be regarded for convenience as an actuator which when set in the center of oscillation 25 of the head 85 is inoperative, and while set on one side of that center will move the grippers in one direction and while set on the other side will move the grippers in an opposite direction. The segmental block has 30 pivotal connection with a link 90 joined by a connecting rod 92 with a plunger 94 supported in bearings in the guide block 40, heretofore referred to as receiving the grippers. A yielding connection is arranged between the plunger 94 and the guide block 35 in order that the force may be yieldingly transmitted to the grippers for moving them laterally. To this end the plunger is connected at 95 with the lower arm of a T-shaped lever 96 that is fulcrumed at 97 to the guide block 40 and supports a crossbar 98. The guide block carries a plunger 99 acted upon by a spring 100, the tension of which is determined by a cap 105, which is 40 adjustable in the block 40. It will now be understood that movement is transmitted from the plunger 94 and its actuating mechanism through the lever 96 and connections to the spring 100, and by the spring, yieldingly, to the guide block 40 and grippers for moving the latter laterally first in one direction and then in the reverse direction in time relation with the closing, uplifting, and overdrawing movements of the grippers 45 which are effected by cams on the same shaft 6 as the cam from which the lateral movements are produced.

The direction of the first movement of the grippers, toward one side of the median line of the machine while holding the stock whereby a plait is formed in one direction or toward the opposite side to carry the stock in that direction to form a plait, is determined by the adjustment of the knee lever 68. The force with which the grip-

pers will be moved laterally will be determined by the tension of the spring 100, and in accordance with this invention novel means is provided by which the operator may readily regulate this tension. As herein shown, see Figs. 3 and 4, the cap 105 is provided on one side with a rack and a pinion 106 is mounted in the guide block 40 in engagement with the rack. The pinion is carried by a shaft 108 on which is an operating arm 110 and a ratchet wheel 112, while a spring-pressed pawl 114 is mounted on the guide block in position for engaging the ratchet wheel to lock the parts in the position to which they are adjusted for determining the tension of the spring 100. The operator can readily increase the tension of the spring by pressing down the operating arm 110, while by depressing the tail of the pawl to free the ratchet the expansion of the spring may be allowed to act automatically to raise the cap 105 any required distance for reducing the tension of the spring and therefore varying the force with which the grippers will be moved laterally. It should be understood that these adjustments may be made while the machine is running and in accordance with the requirements of the work at any particular time,—as, for example, by the condition or 95 nature of the stock to be gripped and plaited. The extent of the lateral movement of the grippers toward either or both sides of the median line of the machine may be determined by an adjustable collar or collars 115, mounted on one of the arms of the guide block 40 which are movable endwise in the forks of the slide rod 42.

For turning the grippers in time relation with their lateral movements to facilitate 105 the plaiting of the stock the link 90 is connected to a lever 120 which is mounted on an adjustable fulcrum block 122 and joined yieldingly at its upper end to a connecting rod 124 that carries a rack bar 125 meshing 110 with rack teeth formed on the peripheral upper end of the gripper bar 13, as illustrated in Fig. 1.

It will now be understood that the grippers have closing, uplifting, and overdrawing movements for engaging and stretching the upper materials and laying them over the last bottom, and that at times the grippers will have lateral and turning movements for plaiting the overlaid upper. 115

It has been explained that the sole is cut away about its margin to form a shoulder and a thin or feather edge on that face over which the upper is laid. The stitches which connect the upper to the sole pass through 125 the upper and into the sole in the angle formed by the shoulder and feather-edge, passing thence through the portion of the sole between the shoulder and the base of the channel and being laid in the channel, 130

where they are covered by the channel lip. It is desirable for the purpose of preparing the shoe for the sewing operation to force the upper material into the angle of union formed by the feather-edge and shoulder. Also, as herein shown, the upper is temporarily secured in lasted position about the toe of the shoe by a binder of wire which is anchored to the foremost tack inserted by the puller-over, the wire being drawn snugly to bind the overworked upper material against the shoulder of the sole. To avoid danger of this wire slipping up out of binding position, it is very important that the upper be forced into said angle of union between the feather-edge and the shoulder thus forming a seat for the wire. To this end the machine herein shown is provided with a presser 130 connected by bolts 131 to the foot 132 of a longitudinally moving slide 134 which is guided in the frame, as shown in Figs. 5 and 7, and connected to the lower end of a lever 135. The lever is pivoted to an adjustable fulcrum block at 136 and is actuated from a groove in a cam 138 on the shaft 6 to reciprocate the presser 130. The cam is formed to advance the presser over the shoe after the grippers have pulled the upper and before they open to release it and to cause the presser to force the upper snugly into the angle of union.

In addition to the presser 130 the machine is preferably provided with a wiper 140 which is rigidly connected to the frame of the machine and forms a stationary block projecting forwardly to the limit of the forward movement of the presser 130. The shoe is fed along with relation to the wiper while held against it, so that it serves to crease the upper into the angle and form it to the desired position. The presser and wiper also serve to seat or to force into binding position the wire by which the upper is held. For this purpose their ends are of a suitable thickness to engage the wire *w*, which, passing from a reel 142 through a suitable tension device 144 and a guide 146, is fastened to a tack, as at *t* in Fig. 7, and held taut in the path of the reciprocating presser and between the end of the stationary wiper and the upper material which stands against the shoulder of the sole. These relations are shown in Figs. 8 and 9, Fig. 8 being a sectional view in a vertical plane passing between the presser and the wiper, and Fig. 9 being a sectional view in a plane passing vertically through the stationary wiper. When the lasting is finished the wire is anchored to a tack *t'* on the farther side of the shoe and securely holds the upper until the shoe is ready to be sewed, by which time the upper material will have become sufficiently set in its lasted position so that it will remain while being sewed. The bottom rest is preferably

equipped with a contact piece or work engaging foot which is rotatable about an axis perpendicular to the face of the sole, and as herein shown the foot 150 has a serrated lower face and is connected by a vertical pivot stud 151 with the shank of the downhold, which, in turn, is clamped in a bracket extending forwardly from the frame. The bottom rest also preferably supports the downhold 152 which extends over the shoulder of the sole and bears on the feather-edge to hold it from being displaced by the upper during the operations of working the upper into lasted position. The downhold is slidably mounted in a guideway in the upper face of the shank of the bottom rest and is adjusted and moved toward and from an operative position by a pinion 154, engaging recesses in the body of the downhold as shown in Fig. 7 and actuated by a handle 156.

In the use of the machine a shoe in the hands of the operator will be presented bottom uppermost to the edge rest 8 and bottom rest 10, the rotatable foot 150 of the bottom rest engaging the sole of the shoe, and the downhold 152 will be advanced into position over the shoulder of the sole into engagement with the feather-edge. The binding wire will be drawn through the tension device 144 and anchored to the tack *t*. The upper materials, including the upper stock and the lining or either of these, as may be required, will then be presented in position to be engaged by the grippers and the machine started. If the upper material is short, so that it cannot be pulled by the normal stroke of the grippers without danger of drawing it out of place on the last, or is weak, so that it is liable to be torn, or if the upper alone is to be pulled without the lining, then the slide 54 will be moved into operative position for shortening the range of the overdrawing movement of the grippers, and preferably the wedge 26 will be out of operative position, as shown in Fig. 1. With the arrangement shown in Fig. 1 the adjustment of the slide 54 and of the wedge 26 is effected by their respective handles 58 and 30, while in the construction shown in Fig. 10 said slide and wedge will be adjusted simultaneously by means of the handle 30 and the connection between the wedge and the rockshaft 50. If a strong pull upon the stock is desired, as, for example, in a case where the upper materials are inelastic or where the lining alone is to be gripped and pulled, the wedge 26 may be adjusted to increase the tension of the spring 23 and the slide 54 will be positioned out of the path of the head 45 of the overdraw rod 42, whereby the force with which the grippers are uplifted will be increased and the grippers may have their full stroke for pulling the upper over

the last. As the lasting proceeds about the toe of the shoe the plaiting mechanism will be thrown into operation by the manipulation of the knee lever 68 and when 5 it is desired to increase or diminish the force with which the grippers are moved laterally for plaiting the handle 110 or the pawl 114 (see Fig. 4) may be conveniently manipulated to adjust the tension of the spring 100 10 by simply pressing down either the handle or the pawl, according as the tension is to be increased or diminished. The pawl will automatically lock the spring at any tension to which it is adjusted. As the lasting proceeds 15 the wire, having been anchored to the tack t , is drawn from the reel through the tension device and the guide 146 and wrapped about the toe of the shoe. The reciprocating presser 130 forces the upper 20 firmly into the angle of union between the shoulder and feather-edge of the sole and preferably presses the wire against the upper to seat it securely in holding position. The wiper 140 remains continuously 25 in engagement with the upper and wire and serves to form the upper into the desired position and to hold the upper from slipping back until the shoe shall have been turned far enough for the wire to 30 bind the upper firmly. The rotatable foot 150 of the bottom rest facilitates the turning of the shoe for presenting successive portions of the upper to the grippers and it will be observed in Fig. 7 that the foot 35 of the bottom rest may be so positioned that it engages the sole approximately at the center about which the shoe is turned in lasting around the toe end of the shoe so that there is little or no occasion for movement 40 of the foot of the bottom rest over the surface of the sole. When the lasting is completed to the farther side of the shoe the wire will be anchored to the tacks t' and then cut from the strand of wire by pre- 45 senting it to the cutting device.

Setting it to the cutting device. The cutting device preferably comprises a stationary cutter 160 and a swinging cutter 162 pivoted at 163. A rod 164 connects the upper arm of the swinging cutter 162 with a lever 165 fulcrumed at 167 and connected by a link 168 and rod 169 with a treadle 170 which is fulcrumed at 171. The treadle also has connection by means of a rod 172 with a starting and stopping mechanism shown in Fig. 12 and which may be of any usual or preferred form. The connection between the treadle and the cutting device and the connection between the treadle and the starting and stopping mechanism are preferably so arranged relatively that one of said parts may be actuated independently of the other, and as herein shown there is sufficient lost motion between the treadle and the starting and stopping mechanism to allow of the cutting

device being actuated without the starting and stopping mechanism being actuated.

Having described my invention, what I claim as new and desire to secure by Letters Patent of the United States is:—

1. In a machine for working an upper over a last, the combination with grippers to seize and pull the upper and means for actuating them automatically to draw the upper inwardly over the edge of the last for laying it in position to be fastened, of means adapted to be adjusted for varying the position to which said actuating means can move the grippers inwardly over the last bottom. 70 75

2. In a machine for working an upper over a last, the combination with grippers and means for actuating them from their gripping position inwardly from the edge of the last to pull the upper over the last, of means adapted to be rendered operative or inoperative for varying the normal extent of the pulling movement while the gripping position remains unchanged. 80 85

3. In a machine for working an upper over a last, the combination with grippers to seize and pull the upper and automatic means for yieldingly actuating the grippers to draw the upper inwardly over the edge of the last toward position to be fastened, of adjustable means adapted to be rendered operative for limiting the overdrawing movement of the grippers. 90 95

4. In a machine for working an upper over a last, the combination with grippers 100 to seize and pull the upper and automatic means for yieldingly actuating the grippers to draw the upper inwardly over the edge of the last toward position to be fastened, of means arranged to be actuated while the 105 machine is running for adjustably shortening the movement which can be effected by the yielding actuating means.

5. In a machine for working an upper over a last, the combination with grippers 110 and means for actuating them from their gripping position inwardly from the edge of the last to pull the upper over the last, of a sliding stop, and means under control of the operator to move the stop toward 115 and from position to shorten the operative stroke of the grippers away from their gripping position.

6. In a machine for working an upper over a last, the combination with grippers, 120 means including a spring for actuating the grippers to pull the upper upwardly, and means including a spring for actuating the grippers to pull the upper forwardly, of devices operatively connected for adjusting 125 the tension of one of said springs and limiting the stroke that can be effected by the other spring.

7. In a machine for working an upper over a last, the combination with grippers, 130

- means including a spring for actuating the grippers to pull the upper upwardly, and means including a spring for actuating the grippers to pull the upper forwardly, of a wedge controlling the tension of one spring, a stop for limiting the stroke effected by the other spring, and means under control of the operator whereby said wedge and stop may be simultaneously adjusted.
10. In a machine for working an upper over a last, the combination with grippers, means for actuating the grippers to pull the upper, and means including a spring to actuate the grippers to plait the upper, of means for regulating the tension of the spring, including a member provided with rack teeth and operatively connected with the spring, a pinion engaging the rack teeth, a hand lever for turning the pinion, and a pawl and ratchet for securing the pinion in adjusted position.
11. In a machine for working an upper over a last, the combination with grippers, means for actuating the grippers to pull the upper, and means including a spring to actuate the grippers to plait the upper, of mechanism including a part adapted to be tripped by the operator for adjusting the tension of the spring, said mechanism being constructed and arranged to permit the spring to expand automatically when said part is tripped.
12. In a machine for working an upper over a last, the combination with grippers, and means for actuating them to pull the upper, of the sliding bar 134, the presser 130 rigidly connected to said bar, the lever 135, and the cam 138 arranged to act through said lever and bar for reciprocating the presser to force the pulled upper into the angle between the feather-edge and shoulder of a sole on the last.
13. In a machine for working an upper over a last, the combination with grippers, and means for actuating them to pull the upper, of the wiper 140 secured rigidly to the frame of the machine in position to project over the shoe bottom and press the upper and the securing wire firmly into the angle of union between the feather edge and shoulder of the shoe sole, the sliding bar 134, the presser 130 attached to said bar, the lever 135, and the cam 138 all constructed and arranged to reciprocate the presser positively both toward and away from the upper.
14. In a machine for working an upper over a last, the combination with grippers, and means for actuating them to work the upper over the last by repeated operations applied to different parts of the shoe, of a bottom rest having a foot for contacting with a sole on the last bottom and relatively to which the shoe is turned in lasting around the end portions of the shoe, said foot com-
- prising a member arranged to turn about an axis sustained perpendicular to the face of the sole when the last is turned as and for the purpose described.
15. In a machine for working an upper over a last, the combination with grippers and means for actuating them to pull the upper, of a bottom rest having a foot for contacting with a sole on the last bottom, said foot comprising a disk having a serrated face for engaging the sole and mounted to turn about a pivot pin sustained perpendicularly to the face of the sole.
16. In a machine of the class described, a starting and stopping mechanism, a treadle, a connection between the said mechanism and the treadle, a cutting device, and a connection between the treadle and the cutting device, said parts being constructed and arranged to permit the treadle to be actuated for operating the cutting device without operating the starting and stopping mechanism.
17. In a machine of the class described, a cutting device, a treadle, a connection between the treadle and the cutting device, a starting and stopping mechanism, a connection between the treadle and the starting and stopping mechanism requiring a movement of the treadle to operate the starting and stopping mechanism other than that required to operate the cutter, whereby one of said treadle-operated parts may be actuated independently of the other.
18. In a machine of the class described, a starting and stopping mechanism, a treadle, a connection between the said mechanism and the treadle, a cutter, a co-operating swinging cutter, a connection between the treadle and the swinging cutter, said two connections being relatively arranged so that the swinging cutter may be actuated independently of the starting and stopping mechanism.
19. A lasting machine having, in combination, grippers to seize and pull the upper, mechanism for actuating the grippers to overdraw the pulled upper across the edge of the last and toward position to be fastened, said mechanism including a spring-actuated rod 42, an abutment on the rod and an adjustable stop for engaging said abutment to limit the movement effected by the actuating spring.
20. In a machine for working an upper over a last, the combination with grippers, of an actuating rod connected therewith, a spring for moving the rod in the direction to cause the grippers to pull the upper, a cam for reversely moving the rod, and a stop readily movable by the machine operator while the machine is running to restrict the movement effected by the spring.
21. In a machine for working an upper over a last, the combination with grippers,

of an actuating rod connected therewith, a spring for moving the rod in the direction to cause the grippers to pull the upper, a cam for reversely moving the rod, a support through which the rod is guided, and a stop block of different thickness in different portions and adapted for adjustment between the frame and a portion of the rod to limit adjustably the movement effected by the 10 spring.

20. In a machine for working an upper over a last, the combination with grippers, of an actuating rod connected therewith, a spring for moving the rod in the direction to cause the grippers to pull the upper, a cam for reversely moving the rod to effect return movement against the resistance of the spring, and a stop arranged to limit the return movement to prevent overthrow from 15 the cam action when the spring is weak.

21. In a machine for working an upper over a last, the combination with grippers, of an actuating rod connected therewith; a spring for moving the rod in the direction to cause the grippers to pull the upper; a cam for reversely moving the rod; and unyielding, relatively adjustable stops 25 for limiting the movement in each direction.

22. In a machine for working an upper over a last, the combination with grippers, of means including a spring for actuating the grippers, and means to regulate the tension of the spring, including a member

against which the spring abuts at one end, a rack on said member and a pinion and lever arranged in position for convenient manipulation to adjust the member while the machine is running. 35

23. In a machine for working an upper over a last, the combination with grippers, an actuating rod connected therewith, a spring for moving the rod in the direction to cause the grippers to pull the upper, of a slidingly mounted cap to compress the spring and having a handled end within 40 reach of the operator while standing in working relation to the machine, and means to retain the lever in adjusted position.

24. In a machine for working an upper over a last, the combination with grippers, of mechanism to actuate the grippers to plait the upper while lasting around the toe portion of the shoe including a spring and means, arranged in position to be manipulated by the operator standing in working 50 relation to the machine, by which the plaiting tension may be increased and diminished as the plaiting progresses.

In testimony whereof I have signed my name to this specification in the presence of 60 two subscribing witnesses.

CHARLES DE MINICO.

Witnesses:

JAMES R. HODDER,
ARTHUR L. RUSSELL.

Correction in Letters Patent No. 1,009,054.

It is hereby certified that in Letters Patent No. 1,009,054, granted November 21, 1911, upon the application of Charles De Minico, of Revere, Massachusetts, for an improvement in "Lasting-Machines," an error appears in the printed specification requiring correction as follows: Page 4, line 111, for the word "peripheral" read *spherical*; and that the said Letters Patent should be read with this correction therein that the same may conform to the record of the case in the Patent Office.

Signed and sealed this 26th day of December, A. D., 1911.

[SEAL.]

C. C. BILLINGS,
Acting Commissioner of Patents.

of an actuating rod connected therewith, a spring for moving the rod in the direction to cause the grippers to pull the upper, a cam for reversely moving the rod, a support through which the rod is guided, and a stop block of different thickness in different portions and adapted for adjustment between the frame and a portion of the rod to limit adjustably the movement effected by the 10 spring.

20. In a machine for working an upper over a last, the combination with grippers, of an actuating rod connected therewith, a spring for moving the rod in the direction to cause the grippers to pull the upper, a cam for reversely moving the rod to effect return movement against the resistance of the spring, and a stop arranged to limit the return movement to prevent overthrow from 15 the cam action when the spring is weak.

21. In a machine for working an upper over a last, the combination with grippers, of an actuating rod connected therewith; a spring for moving the rod in the direction to cause the grippers to pull the upper; a cam for reversely moving the rod; and unyielding, relatively adjustable stops 25 for limiting the movement in each direction.

22. In a machine for working an upper over a last, the combination with grippers, of means including a spring for actuating the grippers, and means to regulate the tension of the spring, including a member

against which the spring abuts at one end, a rack on said member and a pinion and lever arranged in position for convenient manipulation to adjust the member while the machine is running. 35

23. In a machine for working an upper over a last, the combination with grippers, an actuating rod connected therewith, a spring for moving the rod in the direction to cause the grippers to pull the upper, of a slidingly mounted cap to compress the spring and having a handled end within 40 reach of the operator while standing in working relation to the machine, and means to retain the lever in adjusted position.

24. In a machine for working an upper over a last, the combination with grippers, of mechanism to actuate the grippers to plait the upper while lasting around the toe portion of the shoe including a spring and means, arranged in position to be manipulated by the operator standing in working 50 relation to the machine, by which the plaiting tension may be increased and diminished as the plaiting progresses.

In testimony whereof I have signed my name to this specification in the presence of 60 two subscribing witnesses.
